METHOD OF CONDUCTING RESERVOIR PILOT TESTS WITH A SINGLE WELL

Donald H. Henley, Tulsa, Okla., assignor to Pan American Petroleum Corporation, Tulsa, Okla., a corporation of Delaware

Filed June 5, 1961, Ser. No. 114,987
14 Claims. (Cl. 166—4)

The present invention relates to the production of petroleum from subterranean reservoirs by means of secondary recovery methods. More particularly, it is concerned with a method for testing and determining the characteristics of a reservoir such as, for example, the homogeneity or floodability of said reservoir, by the use of a single pilot or test well.

Briefly, one embodiment of my invention involves placing a packer at an intermediate level in the formation to be tested so as to form an essentially fluid-tight seal in the well between the zones above and below the packer. Thereafter, test fluid is introduced into one of said zones, produced into the well via the other, and recovered. In carrying out such a test, the packer may be placed between perforations in a cased well or a sealant may be placed in an open hole section, and that portion of the formation covered by sealant confined by a packer at either end thereof. Such sealing step may, if desired, be accomplished by using an oil base mud, for example, to seal off the zone defined by the packers. Fluid is then injected into the formation, for example, above the upper packer, permitted to flow into the well below the bottom packer, and then produced via tubing through said packers. Alternatively, injection of fluid into the formation may be beneath the lower packer, particularly if a fluid heavier than oil is used, and produced into the well above the upper packer.

In still another embodiment of my invention, the producing formation is notched or underreamed at a level near the base thereof, and thereafter a substantially horizontal fracture is formed out through the formation from the resulting notch. A second notch and fracture are similarly placed at a level near the top of the producing formation. Between these two fractures there is placed a packer on production tubing. If the well is uncased between the fractures, the formation face should be sealed off. Fluid, which may be the same as used in forming the fractures, is then introduced into the upper fracture. The fluid thus introduced which, for example, is lighter than the oil in the reservoir, flows back into the formation and eventually forces hydrocarbons out of the reservoir and into the well via the lower fracture. Injection of fluid through the upper fracture is continued, while hydrocarbons are produced through the lower fracture. In this way, in a relatively short time, for example thirty to forty days, the behavior of a fluid drive agent in a given reservoir can be determined. While fractures are not necessarily essential in carrying out the process of my invention, they provide higher injectivity and shorter test periods. Also, they increase the possibility of increasing the volume of reservoir contacted.

In the drawings, FIGURE 1 represents an oil-producing formation penetrated by a cased well wherein fractures have been made at levels near the top and bottom of said formation.

FIGURE 2 illustrates the manner in which a flooding agent lighter than the oil to be recovered is introduced into the formation.

FIGURE 3 shows a cross-section of the same system as illustrated in FIGURE 2 at a later stage in the process.

FIGURE 4 illustrates still another embodiment of my invention wherein the flooding fluid, which is heavier than

2

the oil to be produced, is injected into the lowermost of two fractures in a formation penetrated by an open hole.

FIGURE 5 is a vertical sectional view illustrating application of the principles of my invention in determining directional permeability of the reservoir.

In any secondary recovery process, preliminary studies of the reservoir to be flooded must be made in order to establish the flooding system that will yield the highest recovery. Ideally, it would be desirable to make such studies under conditions identical with those prevailing in the reservoir. However, in the past this has not been possible. Usually, the reservoir characteristics were best determined by taking a core of the formation under investigation, forcing certain fluids through it and, from the results thus obtained, arriving at a flooding system considered most suitable for the recovery operation contemplated. One chief difficulty with core studies, however, is that it is practically impossible to obtain a core having properties identical to the reservoir rock in its natural state. This is true because in obtaining such a core its permeability is altered to some extent by the drilling mud contacting it during the coring operation. Also, it is impossible to determine from a core such gross reservoir characteristics as directional permeability, since the small core sample may not be representative of larger portions of the reservoir.

Ordinarily when a secondary recovery operation of the above mentioned type is planned, and after all information has been obtained that can be secured by means of core tests, a pilot flood involving usually not more than 4 or 5 acres is initiated. Even with such a small scale test it is generally at least a year before the information necessary for successful performance of the main secondary recovery operation can be obtained. Such an extended period for the procurement of preliminary information not only is expensive to conduct, but the results may indicate a large-scale flood is not feasible; in which case valuable time has been wasted in pursuing an unprofitable project.

One of the outstanding advantages of the process of my invention is that valuable information of the type required to ascertain whether large-scale flooding operations should be conducted can be determined under natural reservoir conditions within a relatively short time. A very desirable feature resulting from being able to study the reservoir under natural conditions is that I am not only able to determine its horizontal and vertical permeability, but it is also possible to ascertain the directional permeability of the reservoir as well. The latter characteristic is extremely important in any secondary recovery operation. Thus, if injection of the flooding agent is conducted under conditions such that said agent travels through the reservoir in the direction of greatest permeability, early breakthrough of said agent occurs, causing poor recovery. On the other hand, if the flooding agent is injected in such a way so that it tends to follow a path essentially perpendicular to the direction of greatest permeability, breakthrough of the flooding agent is delayed, resulting in good sweep efficiency which, in turn, makes possible good oil recovery.

By operating in accordance with the procedure of my invention, the flooding agent is able to contact a large area in the vicinity of the well in a short time. By monitoring the composition of the produced stream, information is provided from which an evaluation of formation properties can be made. For instance, if it is desired to introduce an additive into the flooding agent, say for the purpose of effecting a change in wettability characteristics of the reservoir rock, one must know whether or not such additive tends to be adsorbed onto the rock when contacted by the flooding agent. Accord-

ingly, by plotting the composition of the product stream from the pilot test against time, a measure of the total reservoir volume contacted can be determined since the production ratio is also known. Also, by establishing the amount of said additive recovered in the product stream, the quantity of additive adsorbed can be found. This information then will indicate how much additive will be needed for the main flooding operation in which the main reservoir volume, as a result of other tests, can be established.

The method of my invention will be further illustrated by reference to FIGURES 1 to 5, in which a well equipped with casing 2 is secured in an oil-bearing formation 4 by means of cement 5, or other suitable securing agent. At levels near the bottom and top of said formation, the casing is cut in any known manner, such as by jetting sand-laden oil against the metal surface at 9 and 10. After the casing is cut, the cement and formation back of the casing is notched or underreamed either by the use of abrasive fluids, or by use of a suitable tool, at 12 and 14. These notches create zones of weakness which, when the formation is subjected to hydraulic fracturing at such levels, tend to produce horizontal fractures 16 and 18. In forming fractures at 18, suitable props 20 may be present in the fracturing liquid in order to provide maximum flow capacity. During the fracturing step the fluid is injected into the confined zone formed by packer 22 and the bottom of the well. Fracture 16 may either be propped open in the same manner, or the same result can be obtained if high injection rates are maintained. The fracturing fluid, if injected at 16, should either be composed of a fluid lighter than the reservoir oil, or should comprise a slug of low-penetrating material followed by the light fracturing fluid if losses of the latter to the formation tend to prevent a large-radius fracture. Test fluid or flooding agent, which may be LPG, gas, etc., is forced through tubing 24 and into fracture 16 at a rate such that it is held open. Introduction of the flooding agent is confined to the zone defined by packers 22 and 26. When flooding agent is injected, it flows into the formation in a pattern 30, the nature of which depends upon the characteristics of the reservoir and of the injected fluid. During this step tubing 25 is permitted to remain open so as to create a substantial pressure drop across the formation face at notch 14, thereby aiding in forcing said agent out of the formation and into the wellbore. FIGURE 3 shows a later stage of the process in which the flooding agent and reservoir fluids are ultimately produced into the wellbore via fracture 18. The resulting mixture is removed from the well via tubing 25, and the composition and volume thereof determined. During this time, injection of the flooding agent is continued. As previously mentioned, the operation may require thirty to forty days before a satisfactory study of the produced fluids can be made.

If the fracturing liquid is heavier than the oil to be produced such as, for example, water, it should be injected at a level near the bottom of the formation, as shown in FIGURE 4, to contact a maximum volume of the reservoir. This operation being carried out in open hole requires proper sealing of the formation face between packers 22 and 26. This can be accomplished by filling and sealing the zone between the two packers with oil base mud 32, or other similar material. The oil base mud used to seal the formation face should be maintained at a pressure in excess of the injection pressure of the test fluid into the formation. This will insure a positive seal in the uncased section between the packers. Continued injection of water into fracture 18 results in forcing the oil in the formation upwardly toward fracture 16 and into the open hole via fracture 16 above packer 26, where it is produced through tubing 24. Eventually, a breakthrough of water or other similar flooding agent into the well via fracture 16 occurs. Injection of said agent is

continued until the water-oil ratio has increased to a maximum realistic level.

As previously mentioned, one of the more valuable kinds of information afforded by the process of my invention is concerned with determining directional permeability of reservoir under investigation. Thus, in establishing this characteristic of a given reservoir, perforations are first made at positions 34 and 36, as shown in FIGURE 5, with packer 22 separating the two sets. These may consist of more than one perforation, preferably arranged vertically, at each of the designated positions. After the desired number of such perforations have been made, fluid, such as, for example, LPG, is injected through the perforation or perforations 34 and into the formation. In place of LPG, reservoir oil, if desired, may be substituted to assure that the saturation around the well will remain constant. The time required for breakthrough of LPG and the composition and volume of fluid produced through tubing 25 over a given time interval after said breakthrough are then measured. Next, perforations 34 and 36 are sealed off by any of several known methods. For example, the upper set of perforations 34 could be closed by the use of ball sealers, while the lower set could be sealed off by spotting a small amount of plastic opposite perforations 36 and forcing said plastic therein. After perforations 34 and 36 are adequately blanked off, additional perforations may be made in the casing about 90° from the alignment of groups 34 and 36. Thereafter, injection tests are made in the same manner as described in connection with perforations 34 and 36. By establishing the time required for breakthrough of LPG, and the composition and volume of produced fluid over a given period, such results can be compared with those obtained in the first phase of the process in order to establish the direction of greatest reservoir permeability. If considered necessary or desirable, the above-mentioned procedure may be repeated with new sets of perforations being oriented, this time, for example, about 45° away from the line of the last pair of perforations. In addition to using the breakthrough time and composition and quantity of produced fluids, as mentioned above, the relationship between the pressure drop and the flow rate of fluid in conjunction with other reservoir fluid properties in the two directions 90° apart, are a measure of the directional permeability difference. Actually, directional permeability can be established without using a material such as LPG or water. In other words, such characteristic can be determined without observing the time required for breakthrough. Thus, crude oil may be used as the injection fluid, in which case the pressure drop and flow rate of said fluid can be used as indicators of such permeability.

Alternatively, directional permeability of a reservoir, particularly where the reservoir is of substantial thickness, e.g., 50 to 100 feet, can be determined in accordance with my invention by first setting a packer between two groups of perforations and thereafter carrying out the injection test as described above. The perforations for the second phase of the test may then be placed (at least about 90° away from the former) several feet, e.g., 15 to 20 feet, above or below (but in the same formation) the perforations used in the first phase. Also, the perforations above and below the packer in this second phase of said test should be oriented in a direction different from the alignment of previous sets of perforations. Still a third group of perforations, if the formation under investigation is thick enough, may be placed at a location disposed vertically from the other of said perforations. As in the other two cases, the orientation of the perforations should be different from that employed before, in order to obtain the maximum amount of information.

A further variation also contemplated by my invention involves the making of several pairs of perforations, each group of a pair being separated by a packer or equivalent during the test throughout the thickness of the producing formation if desired. By conducting injection tests with

each pair of perforations throughout the thickness of said formation, important information concerning the characteristics thereof such as, for example, the presence of shale streaks, etc., can be determined.

By the term "cased well," as used in the present description and claims, I intend to include both cased wells and wells having an open hole section opposite the formation under test or investigation. In such open hole section, however, it is to be understood that no direct communication between fractures or perforations via the well is possible.

The fracturing fluids employed in carrying out the process of my invention may vary widely. As examples of such materials there may be mentioned gas, water, water containing agents to alter the natural wettability of the reservoir, light hydrocarbons in liquid or gaseous form such as propane, butane or pentane, or mixtures thereof, for example, LPG.

I claim:

1. In a method for obtaining information on a hydrocarbon-containing formation traversed by a well prior to subjecting said formation to a procedure in which a fluid is to be injected into said formation, the improvement which comprises:

penetrating said formation at a level near the top thereof and at a level near the bottom of said formation,

placing a substantially fluid-tight barrier in said well between said penetrated levels,

injecting a test fluid into one of said levels,

permitting said fluid to be produced into said well via the other of said penetrated levels,

determining the time required for said injected test fluid to break through said formation and into said well,

recovering the fluids thus produced including said test fluid,

measuring the flow rate and pressure drop of the injected test fluid across said formation,

monitoring the composition and volume of said fluids produced into said well during said injection step;

and thereafter, on the basis of the information thus obtained, injecting said fluid into said formation via a well (1) penetrating said formation and recovering hydrocarbon-containing fluids from a second well spaced apart from well (1) and, likewise, extending into said formation.

2. In a method for obtaining information on a hydrocarbon-containing formation traversed by a well prior to subjecting said formation to a procedure in which a fluid is to be injected into said formation, the improvement which comprises:

fracturing said formation at a level near the top thereof and at a level near the bottom of said formation,

placing a substantially fluid-tight barrier in said well between said fractured levels,

injecting a test fluid into one of said levels,

permitting said fluid to be produced into said well via the other of said fractured levels,

determining the time required for said injected test fluid to break through said formation and into said well,

measuring the flow rate and pressure drop of the injected test fluid across said formation,

recovering the fluids thus produced,

monitoring the composition and volume of said fluids produced into said well during said injection step;

and thereafter, on the basis of the information thus obtained, injecting said fluid into said formation via a well (1) penetrating said formation and recovering hydrocarbon-containing fluids from a second well spaced apart from well (1) and, likewise, extending into said formation.

3. The method of claim 2 in which the injected fluid is lighter than the petroleum in said reservoir and said

fluid is injected into the fracture near the top of said formation.

4. The method of claim 3 in which the injected fluid is a hydrocarbon in liquid form when injected.

5. The method of claim 2 wherein the injected fluid is heavier than the liquid hydrocarbons in said formation and said fluid is injected into the fracture near the bottom of said formation.

6. The method of claim 5 in which the injected fluid is water.

7. In a method for obtaining information on a formation containing liquid hydrocarbons penetrated by a cased well prior to subjecting said formation to a procedure in which a fluid is to be injected into said formation, the improvement which comprises:

cutting said casing at a level near the top of said formation and at a level near the bottom thereof, forming a substantially horizontal notch in said formation at the location of each of said levels,

fracturing said formation at said levels, placing a packer in said casing between said notches, injecting a test fluid lighter than said liquid hydrocarbons into said formation via the uppermost of said fractures,

permitting said test fluid to be produced into said well via the other of said fractures,

determining the time required for said injected fluid to break through said formation and into said well, measuring the flow rate and pressure drop of the injected test fluid across said formation,

recovering the fluids thus produced including said test fluid while continuing the injection of said fluid into said uppermost fracture,

monitoring the composition and volume of said fluids produced into said well during said injection step;

and thereafter, on the basis of the information thus obtained, injecting said fluid into said formation via a well (1) penetrating said formation and recovering hydrocarbon-containing fluids from a second well spaced apart from well (1) and, likewise, extending into said formation.

8. In a method for determining the directional permeability of a liquid hydrocarbon-containing formation traversed by a cased well prior to subjecting said formation to a procedure in which a fluid is to be injected into said formation, the improvement which comprises:

penetrating said formation at levels near the top and near the bottom thereof, said penetrating step being carried out so as to produce perforations in said formation at both of said levels and in a common, substantially horizontally oriented path,

placing a substantially fluid-tight barrier in said well between said penetrated levels,

injecting a fluid into one of said penetrated levels, producing formation fluids into said well via the other of said penetrated levels,

monitoring the volume of said fluids produced into said well during said injection step,

determining the pressure drop required to achieve a measured flow rate,

thereafter again penetrating said formation at a level near the top thereof and at a level near the bottom of said formation, said last-mentioned perforating step being carried out at both of said levels so as to produce perforations in said formation in a common, substantially horizontally oriented path but different from the direction of the first-mentioned set of perforations,

injecting a fluid into one of said last-mentioned perforations,

producing said injection fluid and formation fluids, including liquid hydrocarbons, into said well via the other of said last-mentioned perforations,

monitoring the volume of said fluids produced into said well via said other of said last-mentioned per-

forations during said injection step, and determining the pressure drop required to achieve a measured flow rate.

9. The method of claim 8 in which the injection fluid is lighter than said liquid hydrocarbons, and is injected into the perforations near the top of said formation.

10. In a method for obtaining information on a liquid hydrocarbon-containing formation traversed by a well prior to subjecting said formation to a procedure in which a fluid is to be injected into said formation, the improvement which comprises:

sealing off the face of a portion of an open hole section of said well in said formation,
setting production packers at both ends of said sealed-off portion whereby no communication via said well is possible between said packers,
injecting a fluid into said formation at one of said ends, producing formation fluids into said well via the other of said ends,
measuring the flow rate and pressure drop of the injected fluid across said formation,
recovering the fluids thus produced,
monitoring the volume of said fluids produced into said well during said injection step; and thereafter, on the basis of the information thus obtained, injecting said fluid into said formation via a well (1) 20
penetrating said formation and recovering hydrocarbon-containing fluids from a second well spaced apart from well (1) and, likewise, extending into said formation.

11. The method of claim 10 in which the fluid injected is crude oil.

12. The method of claim 10 in which the fluid injected is LPG.

13. In a method for obtaining information on a hydrocarbon-containing formation traversed by a well prior to subjecting said formation to a procedure in which a fluid is to be injected into said formation, the improvement which comprises:

penetrating said formation at a level near the top thereof and at a level near the bottom of said formation,
placing a substantially fluid-tight barrier in said well between said penetrated levels,

injecting a test fluid into one of said levels, permitting said fluid to be produced into said well via the other of said penetrated levels,
determining the time required for said injected test fluid to break through said formation and into said well,

measuring the flow rate and pressure drop of the injected fluid across said formation,
recovering the fluids thus produced, including said test fluid, and
monitoring the composition and volume of said fluids produced into said well during said injection step.

14. In a method for obtaining information on a liquid hydrocarbon-containing formation traversed by a well prior to subjecting said formation to a procedure in which a fluid is to be injected into said formation, the improvement which comprises:

sealing off the face of a portion of an open hole section of said well in said formation,
setting production packers at both ends of said sealed-off portion whereby no communication via said well is possible between said packers,
injecting a fluid into said formation at one of said ends, producing formation fluids into said well via the other of said ends,
measuring the flow rate and pressure drop of the injected fluid across said formation,
recovering the fluids thus produced, and monitoring the volume of said fluids produced into said well during said injection step.
